[57] ABSTRACT

In a switching arrangement of the type having a plurality of coils simultaneously connected to a power source for causing movement of coil-associated switches, the addition of coil response time and release time adjusting means to control selective switching of two input signals to an output without incurring momentary signal interruption at the output. The response and release times are adjusted so that the switches associated with the signal to be connected to the output finish their movement before or at the same time as the start of movement of the switches associated with the signal to be disconnected from the output. The energization response time of each switch controlling relay coil is controlled by a variable resistance in series between the energizing source of power and the relay coil. The de-energization release time of each switch controlling relay coil is controlled by a variable resistance in parallel with said relay coil.

SIGNAL SWITCHING ARRANGEMENT

The present invention relates to an arrangement for signal switching and, more particularly, to a mechanical switching arrangement utilizing electromagnetic relays for the basic frequency band circuit and/or intermediate frequency band circuit included in a microwave communication system.

Various types of switching arrangements for the switchover of microwave communication circuits have been proposed, including those employing diodes adapted to high-speed operation, and those others having electro-mechanical coaxial switches having mercury contact relays or reed relays exhibiting high stability and reliability in operation.

Among the switching elements, the mechanical coaxial switch has particularly high reliability. However, the conventional mechanical coaxial switch employs a plurality of relays, whose response characteristics or operational speed are different from one another. This tends to cause the momentary total interruption of signals at the time of switchover.

An object of the present invention is therefore to provide a signal switching arrangement adapted to avoid the above-mentioned momentary interruption of signals.

Another object of the present invention is to provide a novel signal switching arrangement for use in a stand-by switchover system, which is capable of avoiding the signal level variation even at the moment where the movable contact of the switch is momentarily in contact, so as to avoid the momentary interruption, with both the two fixed contacts coupled to the operating and stand-by transmission circuits.

According to the present invention, there is provided a signal switching arrangement comprising two signal input terminals, one signal output terminal, a predetermined number of switching contacts for selectively connecting one of said input terminals and the output terminal, and a plurality of electromagnetic relays for controlling said switching contacts, a first and a second variable impedance elements respectively connected in series and in parallel with the winding of each said relay, the impedances of said first and second variable impedance means being variable to thereby control the time for the response of the relays to their energization and release, whereby the momentary interruption of the signal is avoided.

An embodiment of the present invention employs, as said relays, two relays of different types, i.e., the bridge type and the non-bridge type, the former providing, in contrast to the latter, a temporary simultaneous connection between the movable contact and fixed contacts at the time of switchover.

The present invention will now be described in detail with reference to the accompanying drawings, in which:

FIGS. 1a and 1b illustrate typical examples of the conventional switching arrangement employing coaxial switches;

FIG. 2 shows a fundamental relay circuit for explaining the principle of the present invention;

FIG. 3 illustrates the time response characteristics of the circuit shown in FIG. 2;

FIG. 4 shows an embodiment of the present invention having four relays;

FIG. 5 is a diagram showing the response time characteristics of the respective relays for the case where the embodiment of FIG. 4 is adjusted to form a non-momentary-interruption type switching arrangement;

FIG. 6 shows an equivalent circuit for illustrating the increase in the signal level at a load observed during the switchover period of the non-interruption type signal switch;

FIG. 7 is shows the response time characteristics of the respective relays employed in the circuit arrangement of the present invention;

FIG. 8 shows another equivalent circuit for illustrating the operation of the embodiment at the moment of the switchover; and

FIGS. 9a, 9b, and 9c show a schematic view illustrating the "bridge" formed between the movable contact and two fixed contacts of a mercury contact relay.

In FIG. 1 showing examples of conventional circuits for selectively connecting one of the two input terminals A and B to one output terminal C, four electromagnetic relay windings RL₁, RL₂, RL₃ and RL₄ connected in parallel as shown in FIG. 1(a) are coupled to a power source E through a switch S. On the other hand, relay contacts rl₁, rl₂, rl₃ and rl₄ of the respective relays RL₃ ~ RL₄ are connected, as illustrated in FIG. 1(b), to form a network lying between the two input terminals A, B and the output terminal C. A resistor having resistance R₀ is inserted between the ground and one of the fixed contacts of each of the relays. The relays RL₁ ~ RL₄ respectively having the contacts rl₁ ~ rl₄ are of the coaxial type with the contacts connected to axial conductors of coaxial cables.

Under the state where the switch S is left open, the input terminal A is connected with output terminal C, with the movable contacts of rl₁ and rl₂ brought to contact with the upper fixed contacts thereof and with the other input terminal B terminated by the resistor R₀. Upon the closure of the switch S to simultaneously energize relays RL₁ ~ RL₄, the terminal B is connected to terminal C while terminal A is terminated by the resistor R₀. As will be apparent from FIG. 1(b), the relays RL₂ and RL₄ are for avoiding the leakage of the switched-off input signal to the output terminal C.

In this circuit arrangement, it should be noted that the response speed is different from one relay to another. This results in the momentary interruption of the signal to be switched over.

In the principal part of the embodiment of the invention shown in FIG. 2, the response to the application and disconnection of the power supply is controlled by additional impedance elements. As shown in FIG. 2, the relay coil RL is shunted by a serially connected diode X and a variable resistor R_p, with a variable resistor R_s connected in series with the relay RL, a power source E and a switch S.

With the addition of the circuit elements X, R_p and R_s, the response speed of the relay RL becomes controllable as shown in FIG. 3, in which the resistance of resistor R_p and R_s is taken along the abscissa, while the response time is taken along the ordinate. The response time to the energization is controlled by adjusting the resistor R_s as shown by curve 1 and the response to the release is controlled by the resistor R_p as shown by curve 2. In this case, the response time of the relay RL to the energization is controlled by adjusting the variable resistor R_s. The variable resistor R_p connected in

parallel with the relay RL does not serve to control the response time to the energization owing to the presence of the diode X which is connected in the reverse direction with respect to the applied voltage. In contrast with this, the response of the relay RL to the release is achieved by discharging through the shunt resistor R_p the energy stored in its driving winding during the application of the power supply.

In the embodiment of the invention shown in FIG. 4, variable resistors $RV_1 \sim RV_4$ corresponding respectively to R_s in FIG. 2, variable resistors $RV_5 \sim RV_8$ corresponding respectively to X are additionally incorporated into the circuit. Further, diodes $X_1 \sim X_4$ are incorporated in order to effect the controls of the response times of the relays $RL_1 \sim RL_4$ to the release respectively independently. An ideal operation will now be explained as to the case where the non-bridge type switch is employed as each of the relays $RL_1 \sim RL_4$. Under this state, the signal circuit $A \rightarrow C$ in FIG. 1(b) is switched to the circuit $B \rightarrow C$ without momentary interruption. Reference is made to a response time chart of the respective relays as shown in FIG. 5. Herein, the terms "the non-bridge type" denote a relay having mere switching construction of a single-pole double-throw type. In this chart, t_1 and t_2 denote starting points of the contacts rl_3 and rl_4 , respectively (the sequence of t_1 and t_2 is not restricted to this example). Time t_3 indicates motional completing points of the contacts rl_3 and rl_4 , which are also starting points of the contacts rl_1 and rl_2 . Times t_4 and t_5 represent completing points of the contacts rl_2 and rl_1 , respectively (the sequence of t_4 and t_5 is not restrictive). As seen from the drawing, the time lag between the starting time points of the contacts rl_1 and rl_2 over the completing time t_3 of the contacts rl_3 and rl_4 causes the signals to be overlapped within the period of the simultaneous connection of the movable contact with the fixed contacts. Conversely, if the former leads the latter, the momentary-interruption arises. If the response time of the relays $RL_1 \sim RL_4$ is appropriately controlled by adjusting the variable resistors $RV_1 \sim RV_4$, the ideal switchover as shown in FIG. 5 is made possible. As regards the setting of the response time of the relays to the disconnection of the power supply as is performed in order to restore the state of the signal circuit after the switchover, quite the same principle is applied.

The ideal switching operation as shown in FIG. 5 is the most preferable for the signal switching arrangement. Practically, however, it is not easy to constantly maintain over a long period of time the mechanical stability of the contacts. Accordingly, a switching arrangement giving rise to non-momentary-interruption even in a longterm operation is suitable for such use. It is to be understood from the foregoing description that, in accordance with the present invention, the signal-overlap-type switching can also be easily realized by merely adjusting the variable resistors.

With such overlap-type switches, however, the two input signals simultaneously appear at the output during the switching operation. In order to flatten the level of the output signals in this case, reference is made to an equivalent circuit in which signals of quite the same phase are combined as shown in FIG. 6. In the figure, the level of the signal applied to a terminating load R_0 at an output terminal C becomes $(2/3)I(1/2)I$ times higher to increase the level by 2.5 dB in comparison

with that when one of signals is carried out. To avoid this defect, a mercury contact relay of the bridge type is employed as, e.g., relay RL_1 , and the response time of the respective relays to the energization are controlled as illustrated in FIG. 7. Then, as shown in the equivalent circuit at the signal combination in FIG. 8, the level variation of the signal applied to the load R_0 is avoided.

The bridge-type mercury contact relay comprises as its principal constituents a switching section with contacts, mercury and high-pressure hydrogen gas sealed into a glass tube. An armature is electromagnetically driven by means of an electromagnetic coil disposed around the switching section. The contact section is always wetted by the capillary action of mercury, and the opening and closure of the circuit are effected by mercury. Therefore, the relay is perfectly free from chattering, and it has high mechanical stability and long life. FIG. 9 illustrates the "bridge" formed between the movable contact and two fixed contacts of the mercury contact relay, with FIG. 9(a) representing a position before motional starting, FIG. 9(b) illustrating an intermediate position of the transfer, and FIG. 9(c) showing a position after the completion of the operation. In the intermediate position, a movable contact is bridged at the central part with two fixed contacts due to the adsorption of mercury. Referring again to FIG. 7, t_1 and t_2 are the same as in FIG. 5. Time t_3 designates the moment of the completion of the contacts rl_3 and rl_4 , and a mercury-bridge starting time of the contact rl_1 . Time t_4 indicates a starting time of the contact rl_2 ; t_5 , a time point at which the bridged mercury of the contact rl_1 is severed; and t_6 , the completion of the motion of the contact rl_2 . The sequence of the time points t_5 and t_6 is not restricted to the illustrated one. Herein, the period of time between t_3 and t_4 is determined to overlap the two input signals. During this period, the resistor R_0 connected to the make-contact of the contact rl_1 serves as a common load for the two signals. As shown in FIG. 8, a current of one-half I is caused to flow through the load R_0 at the point C , and it is of quite the same level at the time of the absence of combination. This principle is similarly applicable to the setting of the response time of the relays to the release. While the mercury contact relay has been herein referred to as the bridge-type relay, it is also possible to employ a relay so designed as to effect the bridging effect without resorting to mercury in the contact section.

We claim:

1. In a signal switching arrangement having a driving circuit of a plurality of electromagnetic relays for selectively connecting one of two input circuits to one output terminal, a signal switching arrangement comprising a plurality of first variable impedance elements connected in series with a driving winding of each said relay, respectively, and a plurality of second variable impedance elements connected in parallel with each said relay, respectively, wherein said first and second variable impedance elements permit separate adjustment so as to control the response time of each said relay and to avoid the possible momentary interruption of a signal at said output terminal at the time of switchover.

2) A signal switching arrangement according to claim 1, wherein said plurality of relays comprise bridge-type and non-bridge-type relays, so combined as to avoid a

variation in the output level of transmission signals at time of switchover.

3. A switching circuit comprising,
  - a first through fourth single pole double throw switches energized respectively by first through fourth relay coils,
  - b said first and second switches being connected in series through their respective make contacts between a first input terminal and an output terminal, when said first and second relay coils are de-energized,
  - c said third and fourth switches being connected in series through their make contacts between a second input terminal and said output terminal, when said third and fourth relay coils are energized,
  - d a power source adapted to be switchably connected in parallel to said first through said fourth relay coils, and
  - e means connected to said relay coils for adjusting the relative response times of said relay coils to energization and de-energization to insure that the relays controlling switches moving from make to break positions don't begin movement until the switches moving from break to make position have completed this motion.
4. A switching arrangement as claimed in claim 3 wherein said means for adjusting comprises,
  - a first through fourth means for individually adjusting the energization response time of said first through fourth relay coils respectively and
  - b first through fourth means for individually adjusting

the release time of said first through fourth relay coils respectively.

5. A switching arrangement as claimed in claim 4 further comprising means connecting the break contacts of said second and fourth switches to ground and individual resistors connected between the break contacts of said first and third switches, respectively, and ground.
6. A switching arrangement as claimed in claim 5 wherein said first switch is a bridge switch of the type which contacts both the make and break terminals simultaneously during movement from one terminal to the other, and wherein the first means for adjusting the energization response time of the first relay coil is set to cause said first switch to complete movement from make to break position after the make-to-break movement of said second switch and substantially simultaneously with the start of make-to-break movement of said first and second switches.
7. A switching arrangement as claimed in claim 6 wherein said first through fourth means for adjusting energization response times comprises first through fourth variable series resistors connected in series, respectively, with said first through fourth relay coils and said power source, and further wherein said first through fourth means for adjusting release times comprises first through fourth variable parallel resistors connected in parallel, respectively, with said first through fourth relay coils.
